UNITED STATES PATENT OFFICE

2,181,026

RESPIRATOR

Nathan Schwartz, New York, N. Y.

Application November 13, 1936, Serial No. 110,557

4 Claims. (Cl. 128—146)

This invention relates to filter type respirators adapted to cover the nose and mouth of the wearer for the purpose of protection against dust, fumes and injurious gases, and is a modification 5 of my copending application for Letters Patent, Serial No. 44,694, filing date October 12, 1935 now Patent No. 2,070,241, of February 9, 1937.

The invention broadly aims to provide a respirator of minimum size and weight, while affording a maximum area of filtration, and is so constructed at connecting points as to make it leak proof, and also affords convenient locations for attached filter units and also for exhalation valve, and provides for easy replacement of filter 15 materials.

More particularly the invention resides in so placing the filter unit as to cause no annoyance to the wearer. Namely a special connecting tube is provided at the set back portion below the 20 nose line for attachment of the filter unit and the exhalation valve. Also space provision is made at the mouth and chin covering portion for attachment of an additional filter unit when that is required. Thereby a very large filter area 25 is made possible, so that the filter material may have greater resistance to air flow for the purpose of greater efficiency.

Another object is to make the connection at the head band and the face piece air tight and 30 smooth.

Another object is to make the connection at the marginal attachment of the filter element leak proof and at the same time easily replaceable.

Another object is to minimize the air spaces in the face covering portion, the filter unit and also in the connecting duct or tube. It is for 35 that reason that one tube is made suitable for the attachment of both the filter unit and the exhalation valve.

With the above recited and other objects in view, reference is had to the following description and accompanying drawing, in which there is exhibited one example or embodiment of the 40 invention, while the claims define the actual scope of the same.

In the drawing:

Figure 1 is a side view of the respirator, showing the attachment of the elastic head or neck band to the face piece of the respirator and also shewing the location of the filter units and exhalation valve.

Figure 2 is a front view and the front filter unit is illustrated, showing its connection to the

downward extending tubular or duct member, located below the nose line.

Figure 3 is a cross section at line 3—3 of Figure 2 and illustrates the filter material attachment and also the filter unit attachment at the 5 suspended tubular part, and also the exhalation attachment at the lower portion of said tubular suspension.

Figure 4 is a cross section of the filter unit which is attached to the mouth and chin covering wall.

Figure 5 is a cross section at point 5—5 of Figure 1, and illustrates the attachment of the elastic head band to the face piece of the respirator.

Figure 6 is a perspective view of the attachment of the head band to the face piece of the respirator and shows the parts separated.

Figure 7 is a rear view of the respirator.

Referring to the drawing by characters of reference, A designates the face piece of the 20 respirator, B designates the filter unit, C designates the exhalation valve, and D designates the elastic head bands.

The face piece A of the respirator is constructed of molded elastic rubber or its equivalent, and it is to be understood that the construction may be of other material such as aluminum or its equivalent. The preferred material is of molded semi-flexible rubber. For attaching the elastic head band a slit 10 is made at both sides 25 of the face piece 10 of the respirator and the free end 11 of the head band D is drawn through the said slit, swatches 12 of sheeting rubber is placed over the slits 10, the free end 11 and the face piece D in the surrounding area of the slit 10. 30 The said swatches 12 are placed in covering relation to the said mentioned parts and adhesively attached one to another. The free end 11 of the head band is folded 13 and is turned to overlap the face piece A of the respirator on the opposite side to where it was inserted. It is to be understood that the insertion of said free end may be made from the outside or from the inside. The swatches 12 are preferably emplaced and attached after the free end 11 is folded 13 35 and therefore the said swatches 12 are preferably covering the free end 11 when in a folded position. However it must be understood that a very good connecting attachment may be made without folding the free end 11. That is, merely 40 inserting said free end 11 into the slit and leaving it unfolded and thus emplacing and attaching the swatches 12. In this instance the free end 11 would also be at the opposite side of the face piece to where it was inserted, but the said 45

50

55

55

free end 11 would be pointing forward instead of rearward.

This method of attaching head bands to respirators is an improvement because leaking possibilities are thereby entirely eliminated and also a smoother face engaging margin at the area of head band attachments is thereby provided, which makes the respirator more comfortable to the wearer.

10 The face piece A of the respirator has a set back 14 which set back is formed providing a recess 15 below the nose line. The said recess creates a vertical nose covering portion 16, and a horizontal nose covering portion 15 and a chin 15 and mouth covering portion 17. The recess 15 is the same as the horizontal nose covering portion 15. The horizontal nose covering portion 15 has a suspended duct or tubular attachment 18. The said tubular part is preferably oval shaped 20 and may be integral with the horizontal nose covering part or may be a separate tube or duct and connected to the said horizontal nose covering part 15. The filter unit B is attached by means of an eyelet 19 to the anterior aspect of the suspended tube 18. An opening perforation 20 is provided in the anterior aspect of the suspended tube 18 and the said opening 20 registers with a similar opening perforation 21 in the filter unit 25 and the eyelet 19 provides sealed connection.

30 The said eyelet 19 is a stiff tubular element with the edges everted at both ends whereby outwardly directed flanges are formed, and these flanges clamp the apertures of the filter plate and the suspended tube forming a leak proof joint thereat. The suspended tube 18 has attached at its lower portion an exhalation flap valve C, which is of the accepted army type exhalation flap valve and sometimes called flutter valve. The method of the attachment of said valve C is as 40 follows. A metal tube 22 is inserted in the lower opening 23 of the suspended tube in order to permanently hold open the said lower end and then the proximal end 24 of the valve is slipped over the lower end 23 of the suspended tube and 45 cemented thereon.

When the concentration of the dust, gases or fumes to be filtered is low the single filter unit with the attached exhalation valve is sufficient for the filtering and separating such dust fumes 50 and gases. But when the concentration of such dust fumes and gases is high, there is need of higher resisting filter material and consequently a larger filtering area is to be provided. Therefore we provide in this invention a second filtering material which is attached to the wall 17, namely the wall that covers the mouth and chin. Two of these filter units may be conveniently attached as is illustrated in Figure 1. These are located one behind the other. The 55 said position is advantageous because an additional filter unit is provided in the same area with almost no extra space and therefore without any hindrance to vision or to movements of the head. It is to be noted that the metal tube 22 which is inserted at the lower end 23 of the suspended tube 18 provides a safe separation between the two filter units and also provides an unobstructed action for the exhalation valve C.

70 Therefore when the injurious matter to be filtered is of high concentration another filter unit is provided at the wall 17. The said wall 17 has an opening 25 and the said opening 25 registers with the opening 21 of the filter unit 75 and an eyelet 19 provides a leak proof connec-

tion. The said eyelet 19 is a stiff tubular element with the edges everted at both ends whereby outwardly directed flanges are formed which flanges clamp the filter unit and the face piece at the openings 21 and 25 and thereby provides a leak proof joint thereat.

5 The filter unit B is preferably of aluminum or an equivalent metal or it may be in certain instances of semi-flexible molded rubber. The inside wall of the filter unit is provided with button elevations 26, which elevations define grooves 27 for the unobstructed flow of air. That is at inspiration the air passes the filter material and its next passage is the continuous air channel 27. The said air channel leads the filtered air to 10 the filter unit opening 21 and the filtered air then passes to the face piece A and then to the respiratory organ of the wearer.

15 Flanged means are provided at the margins of the filter unit for impinging upon the filter material so that unfiltered air shall not pass at the connection of the filter material 28 and the said impinging flange. Two forms of such flanged margins are here shown. First form is an interned flange 29. This interned flange illustrates 20 a hook shaped flange which is very efficient. The applicant's Letters Patent for Separator for filter type respirators or the like, No. 2,035,097, illustrates another form of interned flange for impinging effectively upon a filter material. It is 25 to be noticed that the hook formation is inward and then upwards. The terminal end of the flange is preferably smooth and rounded, so that the filter material may be easily removed.

30 Another form of flange 30 is practical and is 35 equally efficient, namely the flange 30 is inwardly directed as illustrated in Figure 3 and a washer 31 of rubber or of an equally firm material is inserted at the inner side of the interned flange. The said washer is naturally the same size as 40 the flange and is to fit correctly. The said washer 31 is adhesively attached to the inner side of the flange 30.

45 The filter unit elevations are formed by stamping dents 32 at the outer side of the filter unit 45 wall or it may be formed by attaching to the inner side of the said wall several elevating materials such as button or rib shaped metal or hard rubber. The latter form is not shown in the drawing.

50 It is to be understood that more than one air duct or oval tube 18 may be suspended at the horizontal nose covering portion and exhalation valves or filter units may be attached thereto. That is, when the fumes are very dangerous to 55 health further protection is required, and the respirator in such an instance must have greater efficiency. To provide additional efficiency the filter material used necessarily must have a greater resistance to air flow and that makes 60 breathing difficult. In adding filter units the filtration area is increased. The advantage of adding multiple filter units instead of enlarging a single one or two filter units is that one or even two filter units would be too clumsy and 65 inconvenient if the enlargement is made sufficient to provide the large filtering area necessary for dangerously poisonous fumes or gases. Therefore one, two or three oval tubes 18 may be suspended from the said horizontal wall 15, 70 for construction and provision of greater safety against poisonous dust, fumes or gases. In the drawing only one oval tube is shown. If two such tubes 18 are required the horizontal wall 15 would need have a larger antro-posterior diam- 75

ter. That is, sufficiently large to accommodate the additional tube 18. The tube or air passage duct 19 is preferably oval shaped but it may vary and be square shaped or other shape, but must be able to accommodate at its anterior aspect a filter unit and when so required to accommodate a flap valve at its end.

It is to be understood that the connection of the head band D and the hollow mask body A 10 may be accomplished without swatches. That is the free end 11 of the head band is inserted into the slit 10 which slit 10 is to be somewhat smaller in length than the inserted width of the free end 11 and thereby providing a tight fit. When 15 this arrangement is made the application of adhesive cement produces an air tight connection. Additional firmness is provided by applying the swatches 12 and also adhesively attaching them as heretofore described. In the drawing, Figure 20 6 shows the swatches distantly and thereby illustrating the appearance of the head band connection without overlapping swatches.

Having thus described my invention I claim as new and desire to secure by Letters Patent: 25 1. In a respirator, a face piece having an intake port, a filter unit including a wall having an outlet port and a means connecting the filter unit to the said face piece and establishing communication therebetween through said inlet and 30 outlet ports comprising a tubular air duct having apertures with the tubular wall of said conduit being parallel with the said wall of the filter unit and one of said apertures connects with the filter unit while another aperture connects with the 35 face piece and the said filter unit confronts the

said face piece and is spaced therefrom by the said air duct.

2. A respirator having a hollow mask body provided with a recess below the nose line and at least two filter units each of which is provided with an independent air chamber and the said chambers are connected with the body of the respirator at the said recess portion and means provided to maintain a spaced relation between the said filter units.

3. A respirator having a hollow mask body provided with several filter units each of which is provided with an independent air chamber and the said units are located in antro-posterior alignment.

4. A respirator including a face piece having head band attachments for securing the respirator to the face of the wearer and the said face piece being connected with filter units and an exhaust valve at a recessed portion below the nose line, and one of the said filter units connects with the said face piece by means of an air duct, while another filter unit connects with the said face piece at the vertical wall of said recessed portion, and the said filter units have inlet ports and filter materials mounted thereat, and the margins of the said filter materials are removably secured at the margins of said inlet ports, and the said exhaust valve also connects with the said air duct at said recessed portion and the said filter units are in confronting relation one to another and separated by the said air duct and the said exhaust valve.
